UNITED STATES PATENT OFFICE.

JOSEPH H. JONES, OF WINTHROP, MASSACHUSETTS, ASSIGNOR OF ONE-HALF TO
ROBERT BURGESS, OF NEWTON CENTER, MASSACHUSETTS.

CAP-SPINNING FRAME.

1,401,705.

Specification of Letters Patent. Patented Dec. 27, 1921.

Application filed December 27, 1920. Serial No. 433,154.

To all whom it may concern:

Be it known that I, JOSEPH H. JONES, a citizen of the United States, residing at Winthrop, in the county of Suffolk, State of Massachusetts, have invented a certain new and useful Improvement in Cap-Spinning Frames, of which the following is a specification, reference being had therein to the accompanying drawings.

10 The invention relates to cap spinning devices of the class in which a cap and the spindle or bobbin with which it co-operates revolve in unison. More especially, it has relation to that type of such devices in which 15 the cap is controlled vertically by means of a small disk or so-called "whirl," throughout the spinning process, and during the relative traversing movements by which the twisted yarn, in being wound upon the 20 spindle or bobbin, is distributed thereon so as to be built up into the required form of 25 yarn-mass.

The invention consists in a whirl of improved construction; in an improved support 25 for mounting a "whirl" in proper working relations with the cap with which it co-operates; in special means of preventing the whirl from rising from said support during 30 the spinning operation, as well as from being raised by the ordinary attendant upon 35 the spinning frame. Also in means for preventing lubricating oil from working out of the bearing portion of the whirl-support to the exterior of the latter. Also in an im- 40 proved cap.

The drawings show in Figure 1 a view of certain parts of a spinning frame, with an embodiment of the features of the invention applied thereto, the spindle-rail and 45 whirl-supporting rail being in vertical section.

Fig. 2 is a view in plan of the bobbin, cap, whirl, and whirl-support of Fig. 1, and a portion of the whirl-supporting rail.

45 Fig. 3 is a view on a somewhat larger scale showing the parts of Fig. 2, mainly in vertical section.

Figs. 4 and 5, respectively, are a side elevation and a top view of the bolster for the 50 whirl-pintle.

Fig. 6 is a sectional view of the whirl, separately shown.

Fig. 7 is a sectional view of the cap for the whirl-support, separately shown.

55 Figs. 8 and 9 are a side elevation and a

bottom view, respectively, of a tool adapted to be employed for screwing the said cap into place and unscrewing it for removal.

Having reference to the drawings,—

Old and well-known parts shown therein comprise a thread-board 1 having hinged thereto at 2, in usual manner, a block 3 carrying the guide 4 for the yarn α between the front rolls (not shown) and the devices by which the yarn is twisted; also a spindle-rail 5, a bearing-support 6 mounted thereon, and a spinning spindle 7 of sleeve-whirl type mounted in said bearing-support and provided with a band-whirl 7^a around which passes a spindle-driving band 8 by means of which the spindle is rotated; and, also, a quill or bobbin 9 mounted upon the said spindle. The drawings show, further, a cap 10 mounted upon the upper portion of the bobbin and frictionally driven thereby so as to revolve in unison therewith, and a cap-controlling whirl 12 in rolling peripheral contact with the cap. As in my application for U. S. Letters Patent filed November 10, 1919, Serial No. 336,897, the cap is cone-shaped and flares upwardly so that the upper portion of the cap overhangs the peripheral portion of the whirl, whereby the cap is supported vertically by means of the periphery of the whirl.

At 13 is a rail, which is substantially like the ring-rail of a ring-spinning frame, and which carries the whirl-support 14. In practice, in converting over existing ring-frames I retain and utilize the ring-rails 85 thereof by applying whirl-supports thereto.

Referring now to the parts and features which are more immediately involved in the invention,—

The whirl-support 14 is constructed with 95 a base that is adapted to rest upon the top of rail 13, and usually will rest thereon, which is advantageous because of the stability and steadiness which are secured thereby. It has an annular downwardly-extending boss 14^a which occupies a hole in rail 13 around the spindle and bobbin. Such hole usually is concentric with the spindle and bobbin, and in case the rail 13 is a ring-rail the hole will be one of those ordinarily 100 occupied by the base of a spinning ring or its holder. The whirl-support will be retained in place by suitable fastenings, as for instance one or more clamping-screws 105 15. A plurality of screws may be employed, 110

as sometimes in practice in the case of spinning-rings and their holders, and if desired the fastening-means may be of a character and arrangement to provide for adjustment 5 of the whirl-support by which the whirl may be adjusted toward or from the spindle-axis, as may be found advisable or necessary in securing proper working relations between the cap and whirl.

10 The whirl-support is chambered out vertically and within the chamber 14^b is contained a bolster-bearing 16, the lower portion of which is occupied by a steel ball 17 constituting a step-bearing. The whirl is 15 provided with a pintle or journal 18 which extends down within the bolster-bearing and is stepped in its lower end upon the ball 17. The chamber 14^b is of capacity to hold a considerable volume of lubricating oil, and 20 for the purpose of supplying a greater quantity of the latter the base of the whirl-support has formed therein an oil-receiving chamber 14^c communicating by a small passageway 14^d with the main chamber 14^b. 25 Chamber 14^c is furnished with a hinged cover 19. Bolster-bearing 16 is shown as formed with a plurality of radial fins or flanges 16^a, 16^a, 16^a, that engage with the inner surface of the wall of chamber 14^b 30 and serve to centralize the bolster-bearing. These pins or flanges terminate above the bottom of the chamber, leaving the lower portion of the latter unobstructed so as to provide for free circulation of oil within 35 such portion.

The body of the whirl extends in the form of a sleeve 12^a down from the top of the pintle. The said sleeve surrounds the upper portion of the cylindrical shell or wall 40 14^e of the upper portion of the bearing-chamber 14^b, so that the whirl covers the top of the said cylindrical shell or wall and encloses the shell or wall to a considerable distance below said top. This depending body 45 is provided with a ring 20 of material of a character which will not cut or abrade the yarn as it passes between the peripheries of the cap and whirl, and also of a frictional nature suitable for causing the whirl to be 50 rotated through the peripheral contact with the revolving cap.

One feature of invention consists in combining the pintle with the whirl in a positively fixed and permanent manner by casting 55 the whirl upon the top end of a steel pin composing the pintle. By doing this by the process of die-casting I am enabled to secure at very low cost perfectly true and accurate results in making whirls which would 60 not be uniformly true if the parts should be machined and put together in the usual manner by the aid of the machines customarily employed for such work.

The body of the whirl covers and 65 rounds the upstanding wall 14^e of the oil-

chamber 14^b, as already noted, but in order to insure more effectually against the admission of lint and dirt into said chamber, I provide as one feature of the invention a chamber-cover or cap 21 having a peripheral externally-threaded flange which screws down within the internally screw-threaded wall of said oil-chamber. A central hole in the disk of this chamber-covering cap accommodates the pintle of the whirl, which 70 has a close fit within said hole. For the purpose of enabling the whirl to be locked in place so as to prevent it from rising or being raised so long as the cap remains screwed down in place, I form in the pintle 75 just below the disk of the chamber-covering cap an annular groove 18^a, Fig. 6, and apply to the pintle a split ring 30 which partly occupies and contracts within the said groove. Contact of this ring with the under 80 side of the said disk will prevent the whirl from moving upward until the chamber-covering cap has been unscrewed. Preferably the disk of the whirl is closed or continuous, except for one or more small openings 12^e, 12^e, Fig. 2, so that the disk of the chamber-covering cap is covered by that of the whirl and more or less completely concealed and rendered invisible. It also is inaccessible except through the said small 85 openings. To enable the chamber-covering cap to be unscrewed when necessary, I form in the disk thereof a hole or holes 21^a, 21^a, Fig. 7, preferably not going entirely through the said disk. By applying at the top of the whirl a suitable appliance or tool having a projection or projections capable of being passed through the hole or holes in the top of the whirl 90 and engaged in the hole or holes in the disk 95 of the chamber-covering cap, and then rotating the whirl and said cap together by means of the said appliance, the chamber-covering cap may be unscrewed to permit 100 of the removal of it and the whirl together. 105 After replacement of the whirl and chamber-covering cap, the latter may be screwed back into place in like manner to lock the whirl in its working relations again. A suitable appliance or tool for the purpose 110 just noted is shown at 22, Figs. 3, 8 and 9, it comprising a cylindrical body having a central hole 22^a to receive the upstanding central hub of the whirl, a flange 22^b, opposite pins 22^c, 22^c projecting from flange 22^b and 115 adapted to pass through the holes in the body of the whirl and engage within the holes in the disk of the chamber-covering cap, and a flange 22^d that is knurled to facilitate the turning of the appliance or tool 120 in unscrewing the said cap and screwing it back into place. The appliance or tool 22 is applied as in Fig. 3 only when it is required to utilize the same in screwing the 125 cap 21 into place or effecting its removal. 130

At other times it is removed from the whirl, etc.

The split ring 30 simply is allowed to contract into the groove formed around the pinte, and remains therein by reason of its tendency to retain its normal contracted state. It may be forced out of the said groove and drawn off from the pinte whenever it is desired to disconnect the chamber-10 covering cap from the whirl. The parts may readily be recombined inreassembling them for use.

An advantage of the split ring 30 is that it constitutes a radial collar or flange on the pinte from which oil working upward along the pinte flashes off outwardly against the interior of the cap-flange and of the shell or wall of the oil-chamber under the influence of centrifugal force, thereby 20 preventing the oil from reaching the underside of the body of the whirl and working outward thereon so as to escape to the exterior of the whirl-support, to collect thereon, accumulate dust and lint, etc.

25 The improved cap 10 shown in the drawings is characterized by having its downwardly tapering conical exterior formed with a flare or taper making a greater angle with the longitudinal axis of the cap than 30 that of the conical cap of my application aforesaid filed November 10, 1919. The increased angle is secured through making the cap with a conical portion 10° substantially less in length than the length of the body 35 of the cap, as shown in the accompanying drawings, which enables the desired angle to be attained without any inconvenient reduction in the diameter of the lip of the cap at its open lower end or increase in the 40 diameter of the large part of the cone. The total length of the cap itself must be sufficient to permit the cap to be formed with an internal chamber sufficient in its vertical measurement to accommodate the total 45 length of the conical nose of the filling-mass wound upon the bobbin. In other words, the vertical measurement of the said chamber must be somewhat greater than the length of the traverse by which the yarn is 50 distributed up and down to produce the said conical nose in winding upon the bobbin. In the illustrated embodiment of this feature of invention, the conical shape of the cap is confined to the upper portion of the cap, 55 the lower portion of the exterior of the latter being cylindrical.

The primary aim in increasing the angle of the taper or flare of the conical exterior of the cap is to eliminate tendency to wedging between such exterior and the whirl. 12. With a slight taper on the exterior of the cap, the latter tends to work downward in accordance with the principle involved in the behavior of a belt traveling around a

cone pulley. This downward tendency is 65 accompanied by a tendency to the wedging aforesaid. The result of the wedging is primarily a tendency to crowd the cap, bobbin and spindle sidewise away from the axis of the pivot. This causes the pinte of the spindle to bear more against one side of its bearing support than against the other sides thereof, which not only affects the general running of the spindle but tends to produce wear between the spindle and its bearing. 75 A natural result is an increased consumption of power which is appreciable in the case of the entire spinning frame and is multiplied with the number of frames. An incidental effect is a more or less complete neutralization of the capacity of the spindle to find its own center in rotating, the consequence of which is greater noise, etc. in the working of the frame. The spindle does not run on its true center of rotation, which would be 80 the center of gravity; it chatters, fails to run smoothly, and probably the attainable speed is reduced. The wedging action, by producing more or less of a cramping effect between the cap and the bobbin, tends to 85 cause the cap to turn at the same rate of speed as the spindle and the bobbin, and by diminishing the differential affects the tension so that the action is not as good as when the difference or differential is greater. 95

By eliminating wedging and consequent binding or cramping of the cap upon the bobbin, freer turning of the bobbin within the cap is permitted, which results in a better winding-on action and in a better tension of the yarn. 100

The details of the construction of the devices in which the features of the invention are embodied may be varied more or less in practice. 105

What is claimed as the invention is:

1. The combination with a rotating spinning element, a cap surrounding said element and rotating in unison therewith, a rail having an opening through which the 110 said element extends, a whirl-support having a base adapted to rest upon said rail and a boss encircling the said element and occupying the opening in the rail, such whirl-support also having a chamber containing a bearing, and a supporting whirl for the said cap, having a pinte working in the said bearing. 115

2. The combination with a rotating spinning element, a cap surrounding said element and rotating in unison therewith, a rail having an opening through which the 120 said element extends, a whirl-support having a base adapted to rest upon said rail and a boss encircling the said element and occupying the opening in the rail, such whirl-support also having a chamber containing a bearing and a communicating 125

- chamber constituting an oil-reservoir, and a supporting whirl for said cap, having a pintle working in the said bearing.
3. The combination with a rotating spinning element, and a cap surrounding said element and rotating in unison therewith, of a chambered whirl-support containing a bolster-bearing and a ball-step, and a whirl supporting said cap, having a pintle fitting said bolster-bearing and stepped upon the ball-step.
4. The combination with a rotating spinning element, and a cap rotating in unison with said element, of a whirl-support having a chamber, a bolster-bearing within said chamber having radial fins or flanges which engage the wall of the chamber, and a whirl supporting said cap having a pintle fitting the bolster-bearing.
5. The combination with a rotating spinning element, and a cap rotating in unison with said element, of a whirl-support having a chamber, a bolster-bearing within said chamber having radial fins or flanges which engage the wall of the chamber, a ball-step at the lower end of said bolster-bearing, and a whirl supporting the cap having a pintle fitting the bolster-bearing and stepped upon the ball-step.
6. The combination with a rotating spinning element, and a cap rotating in unison with said element, of a supporting whirl constructed for peripheral contact with the cap and comprising a whirl-body and a pintle combined with each other in fixed and permanent manner by casting the whirl-body upon the top end of the pintle.
7. The embodiment with a rotating spinning element, a cap rotating in unison therewith, and a whirl-support having an oil-chamber furnished with an upstanding wall and a bearing, of a cap-supporting whirl having a pintle which works in said bearing and a sleeve which fits over and incloses said upstanding wall, and an oil-chamber cap apertured to fit the pintle, seating in the upper part of the chamber, and sealing the top of the latter.
8. The combination with a rotating spinning element, a cap rotating in unison therewith, and a whirl-support having an oil-chamber furnished with an upstanding wall and a bearing, of a cap-supporting whirl having a pintle which works in said bearing and a sleeve which fits over and incloses said upstanding wall, and an oil-chamber cap apertured to fit the pintle, screwing into the upper part of the chamber, and sealing the top of the latter.
9. The combination with a rotating spinning element, a cap rotating in unison therewith, and a whirl-support having an oil-chamber furnished with a bearing, of a cap-supporting whirl covering the top of the oil-chamber and having a pintle which
- works in said bearing, and an oil-chamber cap apertured to fit the pintle, screwing into the upper part of the chamber and sealing the top of the latter, said oil-chamber cap constructed for engagement by a tool for 70 screwing it into and out of place within the oil-chamber, and said whirl apertured for insertion of an engaging portion of said tool into engagement with the cap to effect screwing of the latter into place and unscrewing thereof for its removal.
10. The combination with a rotating spinning element, a cap rotating in unison therewith, and a whirl-support having an oil-chamber furnished with a bearing, of a 80 cap-supporting whirl covering the top of the oil-chamber, having a pintle which works in said bearing, and also having an upstanding central hub, and an oil-chamber cap apertured to fit the pintle, screwing into the 85 upper part of the chamber and sealing the top of the latter, said oil-chamber cap constructed for engagement by one or more engaging portions of a tool seated upon said hub to effect screwing of the oil-chamber cap into place and unscrewing for its removal, said whirl also having a hole or holes through which the engaging portion or portions of said tool may be inserted into engagement with the oil-chamber cap. 95
11. The combination with a rotating spinning element, a cap surrounding said element and rotating in unison therewith, a whirl-support having a chamber provided with a bearing, and a cap-controlling whirl 100 having a pintle working in said bearing, of a cap or cover for said chamber fixedly combined in removable manner with said whirl-support and having an aperture occupied by said pintle, and means detachably applied to 105 the pintle below the chamber-cap or cover, adapted to engage with the latter to prevent accidental rising of the whirl.
12. The combination with a rotating spinning element, a cap surrounding said element and rotating in unison therewith, a whirl-support having a chamber provided with a bearing, and a cap-controlling whirl having a pintle working in said bearing, of a cap or cover screwed into said chamber 110 and having an aperture occupied by said pintle, and means detachably applied to the pintle below the chamber-cap or cover, adapted to engage with the latter to prevent 115 accidental rising of the whirl.
13. The combination with a rotating spinning element, a cap surrounding said element and rotating in unison therewith, a whirl-support having a chamber provided with a bearing, and a cover for said chamber removably secured in place and having a hole there-through, of a cap-supporting whirl having a 120 pintle occupying the hole in said cover, working in said bearing, and recessed at a point below the cover, and locking means detach- 125
- 130

ably engaging in the recess of the pindle to prevent, through engagement with the cover, accidental rising of the whirl.

14. The combination with a rotating spin-

5 ning element, a cap surrounding said element and rotating in unison therewith, a whirl-support having a chamber provided with a bearing, and a cover for said chamber removably secured in place and having a hole there-
10 through, of a cap-supporting whirl having a pindle occupying the hole in said cover, working in said bearing, and annularly grooved below the cover, and a split ring clasping the pindle within the groove and serving to lock
15 the whirl from rising.

15. The combination with a rotating spin-
ning element, a cap surrounding said element and rotating in unison therewith, and a
20 whirl-support having a chamber provided with a bearing, of a cap-supporting whirl having a pindle occupying the said bearing and provided with a radial collar or flange from which oil working upward upon the pindle is flashed in the rotation of the whirl
25 and thereby prevented from reaching the whirl-body.

16. The combination with a rotating spin-
ning element, a cap surrounding said element and rotating in unison therewith, a whirl-
30 support having a chamber provided with a bearing, and a chamber-cover having a hole through the same, of a cap-supporting whirl having a pindle occupying the said bearing and provided with a radial collar or flange
35 from which oil working upward upon the pindle is flashed below the cover in the rotation of the whirl and thereby prevented from reaching the whirl-body.

17. The combination with a rotating spin-
40 ning element, a cap surrounding said element and rotating in unison therewith, having a downwardly tapering conical portion, and a whirl-supporting and controlling said cap vertically wholly through rolling peripheral
45 contact with said conical portion substan-
tially above the lip or open mouth of the cap,

said conical portion substantially less in length than the body of the cap and thereby making an increased angle with the axis of the cap.

18. The combination with a rotating spin-
ning element, a cap rotating in unison there-
with, and a whirl-support having an oil-
chamber furnished with a bearing, of a cap-
supporting whirl covering the top of the oil-
chamber and having a pindle which works in
55 said bearing, and an oil-chamber cap aper-
tured to fit the pindle, screwing into the up-
per part of the chamber and sealing the top
of the latter, said oil-chamber cap externally
constructed for engagement by a tool for
60 screwing it into and out of place within the
oil-chamber, and said whirl apertured for
insertion of an engaging portion of said tool
into engagement with the cap to effect screw-
ing of the latter into place and unscrewing
65 thereof for its removal.

19. The combination with a rotating spin-
ning element, a cap rotating in unison there-
with, and a whirl-support having an oil-
chamber furnished with a bearing, of a cap-
supporting whirl covering the top of the oil-
chamber, having a pindle which works in
70 said bearing, and also having an upstanding
central hub, and an oil-chamber cap aper-
tured to fit the pindle, screwing into the up-
per part of the chamber and sealing the top
of the latter, said oil-chamber cap externally
constructed at its top for engagement by one
75 or more engaging portions of a tool seated
upon said hub to effect screwing of the oil-
chamber cap into place and unscrewing for
its removal, said whirl also having a hole or
holes through which the engaging portion or
80 portions of said tool may be inserted into en-
gagement with the oil-chamber cap.

In testimony whereof I affix my signature
in presence of two witnesses.
